CARL OTTO, OF ESSEN-RUHR, GERMANY

COKE OVEN

Application filed April 12, 1928, Serial No. 269,485, and in Germany March 28, 1927.

This invention relates to an improved construction of coke ovens. The considerable enlargement practiced in the last few years, of the cross-sectional dimensions of the horizontal chambers of chamber coke ovens serving to produce gas and coke, both as to the height and length of the chambers, results in an increase of the chamber content up to twice that of the hitherto usual one employed. Furthermore, due to the notable improvements in heating the coking chambers the duration of the carbonizing period could be reduced about one half. These two circumstances result in an extraordinary increase of the quantity of the gases of distillation produced during coking.

With the chamber ovens hitherto used, the floor and cover of the chambers extend in a straight horizontal plane. Furthermore, the surface of the charge is likewise kept horizontal, this being obtained, when the coal is charged from the cover, by subsequently levelling the charge, and, when stamped coal is to be coked, by uniformly stamping it in the stamping machine. In both these cases the free space existing between the surface of the charge and the chamber cover, the so-called gas-collecting passage, has an oblong shape which is of the same height throughout. Due to this shape of the gas-collecting passage, however, the distillation gases which collect near the gas outlet opening of the chamber cover from all portions of the chamber, are blocked at this opening. This causes a decomposition of the gases and objectionable differences of pressure within the coking chamber.

Now the invention has for its object to avoid this drawback with certainty and consists substantially in that the cross-sectional area of the gas collecting passage is increased toward the gas outlet opening provided in the chamber cover, either by suitably constructing the cover or shaping the surface of the charge, or by doing both. By this arrangement the distillation gases are drawn off without being blocked in the above-mentioned degree, so that any decomposition of the gases or differences of pressure within the chamber are prevented and an increased

yield of gases and by-products, particularly ammonia, is obtained.

The enlargement of the gas-collecting passage may be obtained, in case stamped coal is coked in horizontal chamber ovens, by so stamping it in the stamping machine, that the stamped coal charge introduced in the chamber has a height that decreases toward the gas outlet opening. Furthermore, the lower portion of the cover adjacent to the chamber may recede toward the gas outlet uniformly or stepwise, or both these measures may be taken in common.

A chamber oven installation adapted to carry out the invention and in which the coal to be coked is introduced in the chamber in the usual manner from the oven cover through a plurality of charging holes, is illustrated by way of example in the accompanying drawing.

Figure 1, is a cross-sectional view of a coke oven, taken in the direction of the oven battery.

Figure 2, is a vertical longitudinal section, showing the gas collection passage increasing in area toward the gas outlet, with the levelling bar in place, and

Figure 3, is a fragmentary cross-sectional view showing the enlarged gas collection passage in dotted lines.

The horizontal coking chamber *a* is closed in the usual manner at its front ends by doors *b*, a closeable levelling hole *b*¹ being provided in the door *b* located on the pushing machine side of the battery. In the cover *c* of the chamber *a* are provided the charging holes *c*¹ for the coal to be coked, and the outlet *c*² for the distillation gases produced during the carbonizing period. An ascension pipe (not shown) conducting the gases to the hydraulic main is connected as usual to the outlet *c*², the latter being located near the levelling hole *b*¹. In the embodiment illustrated the enlargement of the gas-collecting passage *e* is obtained by the lower portions of the sections of the cover *c*, located between the individual charging holes *c*¹, being set off stepwise from the chamber toward the gas outlet *c*², as clearly to be seen from the drawing. The bar *d* serving to level the charge may have a

cross section which corresponds to this enlargement, that is, which increases in height from its free end. This affords the further advantage of the levelling bar d having a notably increased resistance to bending stresses than hitherto.

In the described case the charge is levelled in the usual manner, so that the surface of the charge extends in a straight horizontal plane.

- 10 In the case, however, that the increase in area of the gas collecting passage, obtained by the described tapering of the cover is not sufficient, the surface of the charge may be levelled so as to decline toward the gas outlet
- 15 c^2 . This may be obtained in the simplest manner by designing the levelling bar as a freely suspended body having an underside tapering toward its free end. In this manner a body of at least approximately uniform
- 20 resistance to bending stresses is obtained.

It may be further of advantage, in particular with chambers of very great length, to not arrange the gas outlet in the proximity of a front end of chamber a , but about in the middle thereof. By this arrangement differences of pressure within the chamber, which differences might cause gases to pass over into the adjacent heating walls, are excluded as far as possible. The increase in area of the gas collecting passage is suitably obtained in this case merely by raising the lower portion of the cover adjacent to the chamber from both front ends toward this middle gas outlet. Of course, levelling devices may also be provided on both sides of the chamber, which devices may be constructed in the above-described manner.

What I claim, is:—

1. A horizontal coking chamber provided with a cover and a gas offtake passing through said cover and communicating with the chamber, the underside of the cover being progressively higher from a point remote said offtake to the point where said offtake communicates
- 45 with the chamber.

2. A horizontal coking chamber provided with a cover and a gas offtake through said cover at one end thereof, the underside of the cover being progressively higher from a point
- 50 intermediate the ends of the chamber to the said end.

3. A horizontal coking chamber provided with a cover having a plurality of charging openings spaced longitudinally of the cover
- 55 and a gas offtake at one end thereof, the underside of the cover on the side of each of the charging holes towards the offtake being higher than the bottom of the cover on the opposite side of the charging hole.

- 60 In testimony whereof, I have signed my name to this specification.

CARL OTTO.
